DAVID R. SMITH, OF SAN FRANCISCO, CALIFORNIA, ASSIGNOR TO HIMSELF AND NORBERT LANDRY.

Letters Patent No. 93,016, dated July 27, 1869.

IMPROVED VELOCIPED.

The Schedule referred to in these Letters Patent and making part of the same.

To all whom it may concern:

Be it known that I, DAVID R. SMITH, of San Francisco, in the county of San Francisco, and State of California, have invented certain new and useful "Improvements in Velocipedes;" and I do hereby declare that the following is a full and exact description of the same, reference being had to the accompanying drawings, and to the letters of reference marked thereon.

The nature of my invention is to provide an improved velocipede, so constructed that it can be easily propelled, and its course directed from right to left, at the will of the operator.

My invention consists of a light, oblong, wood frame, resting on a double-crank axle, mounted on wheels, and having a steering and supporting-wheel at the front or back end of the frame.

The frame is supported above and below by stay-rods, attached to the frame, and a vertical forked brace-bar.

The axle is provided with a coupling at each side, to throw the wheels in and out of gear, by the same movement that changes the course of the steering-wheel.

These couplings are actuated by jointed braces and arms, having forked ends that surround the axle, and, when uncoupled, are thrown back into position by springs.

The double cranks are constructed on the axle, between the side-pieces of the frame, and from them depend the connecting-rods, to which the treadle-levers are attached; the ends of these levers being connected to a cross-rod, which is supported by vertical arms, attached to the frame.

The driving-wheels are held to the axle by set-screws, operating in slots.

The naves or hubs are constructed with two circular flanges, from which radial arms extend, held by set-screws.

The spokes proper are constructed of wire, and pass through the felloes of the wheel, and back, forming a loop around them, and passing down to the radial arms, around which the wires are tied.

The steering-wheel is composed of a hollow pipe, and works in a forked brace that is pivoted to the front end of the frame.

The axle of this wheel is a right and left-hand screw, and is provided with a nut-head for regulating the tension of the spokes.

Two flanges are connected to the axle, which are similar in construction to those of the driving-wheels, but no radial arms extend from them, and the ends of the wire spokes pass through holes in the flanges, to which they are tied, and are doubled around the inner portion of the pipe or rim, in a manner similar to that described on the driving-wheels.

Referring to the drawings—

Figure 1, sheet 1, is a plan.

Figure 2, sheet 1, represents a side elevation.

The figures on sheet 2 are parts in detail.

The frame A is oblong in shape, and is constructed of wood, having sufficient strength to resist the necessary strain, and is connected to the axle by collars B B.

The frame is, however, strengthened by diagonal rods C C C C, extending from a forked brace, D, at the top of the frame, and confined to each corner.

Longitudinal strengthening-rods E E also extend at each side of the frame, from end to end, passing beneath the treadle-bar.

By this means the downward pressure and strain are very much relieved, and an elasticity is imparted to the frame.

The axle F is provided with a double crank, F' F', which carries the connecting-rods G G.

The connecting-rods are provided with a spring, H H, which relieves the legs of the operator from the jar of the machinery in passing over rough places.

The fulcrum of the treadle-levers I I I is a rod, I, to which they are hinged.

The rod I' is supported by vertical arms I'', attached to the frame.

In their operation, these treadles act as levers of the second kind, the foot or power being applied at P, and weight or resistance at W, and the fulcrum at F.

By the use of this kind of lever, instead of those of the first or third kind, less space is required, and the motion obtained with less weight of material.

To the axle, at each side of the frame, are attached friction-clutches or couplings J J, which engage the inner ends of the hubs, whereby the wheels are thrown in and out of gear.

The couplings are moved by forked arms k k, and when uncoupled, are thrown back into gear again by rubber springs L L, which surround the axle, back of the forked arms, and react against the collars L' L'.

To the ends of the arms are pivoted double cross-bars M M, which slide, one on top of the other, in straps attached to the frame.

These bars are moved by means of a vertical cam, N, which works in slots, and extends up through a cross-piece and tiller, or steering-bar, O, to each end of which are attached tiller-ropes or wires P P, and connect with the turn-bar, which is pivoted to the steering-wheel at the front or rear end of the machine, according to the direction in which it is headed, as it will run either end first.

By this device, it is intended to change the course or the machine, right or left, by one movement of the tiller-bar, which turns the steering-wheel, and, at the same time, uncouples one wheel, and thereby reducing the power necessary to propel the machine in deviating from a straight course, and also admits throwing a larger proportion of the weight upon the driving-

wheels, and thus permitting the use of a smaller guide-wheel, and consequently reducing the weight of the parts.

The construction of the driving and steering-wheels R R' is of a peculiar character. The hubs or naves of the driving-wheels are provided with two flanges R" R", which are pierced for short radial arms S S S, that are hollow, and to which the ends of the iron wires or spokes T T are tied.

The wires pass through the felloes and back, and form a loop around it, to prevent the slipping of the wire; and one end of the spoke is tied to one radial arm, and the other end to the opposite arm, on the flange at the side of the wheel.

The wire spokes are tightened or loosened by a set-nut, U, on the inner face of the flange, which admits of drawing the radial arms downward, to regulate the tension of the wires, to prevent the wire from cutting into the felloe. Where a wooden felloe is used, a metal plate is placed under it, (shown in red on sheet 2.)

The construction of the steering and end-supporting wheel R' is similar to that of the driving-wheels, the spokes being made of wire W W, and tied to the two flanges a a, (no radial arms appear in this wheel,) and loop around the inner portion of the rim V', through openings made for that purpose, the rim being a bent, hollow pipe.

The wheel is supported, and has its bearings for the axis, the bent bar Y.

The axis X is a right and left-hand screw, with a centre nut-head for turning it, which tightens or loosens the spokes, by spreading apart or drawing nearer the flanges a a.

The object sought to be attained in this construction of driving and steering-wheels is, lightness and durability, and by its elasticity, relieves, in a measure, the jar and rattle so common to other constructions in passing over rough places.

This construction also, in connection with the wire strengthening and bracing-rods, imparts to the whole machine great strength, with elasticity and light weight.

Having thus described my invention,

What I claim, and desire to secure by Letters Patent, is—

In the velocipede as constructed, and in combination therewith, the friction-clutch J J, spurs L L, arms K K, cross-bar M M, cam N, guide-wheel V, with hollow rim R' and axle X, arranged and operated substantially as described.

In witness whereof, I have hereunto set my hand and seal.

DAVID R. SMITH. [L. S.]
